UNITED STATES PATENT OFFICE.

FRITZ LUBBERGER, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

PAY-STATION TELEPHONE SYSTEM.

1,186,484.

Specification of Letters Patent. Patented June 6, 1916.

Application filed October 18, 1906, Serial No. 339,512. Renewed September 12, 1913. Serial No. 789,546.

To all whom it may concern:

Be it known that I, FRITZ LUBBERGER, a citizen of the United States of America, and resident of Chicago, Cook county, Illinois, have invented a certain new and useful Improvement in Pay-Station Telephone Systems, of which the following is a specification.

My invention relates to telephone systems in general, but more particularly to automatic or semi-automatic telephone exchange systems, and especially to systems in which provision is made for pay-stations—that is to say, substations at which telephone service can be had only by the deposit of a coin in the controlling mechanism thereof.

Generally stated the object of my invention is the provision of an improved and highly efficient pay-station telephone exchange system.

Special objects are the provision of means whereby a calling subscriber renders his talking circuit inoperative, and whereby said circuit remains inoperative until after the called subscriber answers, and until the calling subscriber then deposits a coin in the controlling mechanism; the provision of means whereby a calling subscriber may call the trouble operator without being compelled to deposit a coin in the slot of the mechanism containing the controlling mechanism; the provision of means whereby if a calling subscriber calls a busy line and gets a busy-signal, he may then upon hanging up his receiver restore the telephone apparatus to normal condition, leaving the same in readiness to receive a call; and the provision of certain details, combinations and features of improvement tending to increase the general efficiency and serviceability of a telephone exchange system of this particular character.

To the foregoing and other useful ends, my invention consists in the matters herein-after set forth and claimed.

In the accompanying drawings, Figure 1 shows diagrammatically a calling substation and a called substation of my improved type connected with a central office. Fig. 2 is a front elevation of a pay-station attachment embodying the principles of my invention. Fig. 3 is a left-hand sectional elevation of the said attachment. Fig. 4 is a right-hand sectional elevation of the said attachment. Fig. 5 is a detailed section

showing certain parts in a normal position. Fig. 6 is a perspective view of the frame to which the magnets and switching parts of the device are attached. Fig. 7 is a front elevation of the conduit through which the coin travels. Fig. 8 is a top view of the same section. Fig. 9 is a bottom view of the same section. Figs. 10, 11, 12, 13 and 14 are detail views of the said device.

At the substation #500 the locking relay 2 and the releasing relay 3 of the coin-collecting device F are shown. The armature 4 of the said locking relay is normally unlocked, as shown at the substation #220, but when the relay 2 is energized said armature is attracted, as shown at the left in Fig. 1, and locked by the locking armature 5, which latter is pressed to the right by the spring 6. When the relay armature 4 is locked the springs 7, 8 and 9 which it controls are forced together. The springs 7 and 8 when together short circuit the secondary winding 10 of the induction-coil 11, and the closure of springs 7 and 9 shunts the receiver 12 through the resistance-coil 13. Being locked, the armature 4 may be unlocked by the falling of a coin 14, which latter in its downward course presses the stock 15 of the locking armature or latch 5 to the right, driving the angled terminal 16 to the left, permitting the armature 4 to resume its normal position, due to the tension of the spring 7. Said armature 4 may also be unlocked by the release relay 3. Said relay has two windings 17 and 18, the latter included in the subscriber's switch release circuit, whereby the said release relay 3 may be energized when the subscriber hangs up his receiver; and the former (17) in series with the line, to be energized whenever the operator at E answers.

In the central office the calling substation #500 has allotted to it the first-selector A. It will be noticed that the central battery B has its positive terminal preferably grounded. The operating relays of the central switches are normally connected to the non-grounded terminal of the said battery, so that the subscriber by grounding his line conductors may operate the said switches, as is usually the custom in systems of the class in connection with which I have elected to illustrate my invention. In addition to the said first-selector there is shown at the central office a connector C, and another

first-selector D allotted to the called line. The cord circuit E of the trouble operator is also shown just above the connector switch.

5 The coin-collecting device comprised in my invention may be considered as an attachment with suitable terminals which may be electrically connected with the circuits of the telephone proper.

10 The substations in the system may be of any suitable or approved type. The substation #500, for instance, is provided with the usual talking circuits, switch-hook for controlling said circuits, and with a calling 15 and signaling device. The switch-hook 19 is provided with a number of cam arms 20, 21, 22 and 23 for controlling the circuits. The cam arm 22 normally engages the ringer circuit spring 24, which circuit includes the 20 ringer 25, said ringer being normally bridged across the subscriber's line. The cam arm 21 normally controls the ground springs 26 and 27 for putting the subscriber's calling device in connection with the ground terminal G of the battery B. Also, the cam arm 20, when the switch-hook is up, controls the local circuit springs 28 and 29. The release springs 30, 31 and 32 are controlled by the cam arm 23, for releasing 25 the switching apparatus at the central office, as well as for energizing the release magnet 3 of the coin-collecting attachment. In the local circuit there are, of course, included the transmitter 33, the local battery 34, and 30 primary winding 35 of the induction-coil 11. In the secondary circuit that comprises the receiver 12 and the secondary winding 10 there is included a condenser 36, for keeping the subscriber's line conductors open.

35 The subscriber's calling device may be of any suitable type. I have represented said calling device as comprising a couple of push-buttons 37 and 38, and a couple of springs 39 and 40 that normally engage the contact points 41 and 42, respectively. Said springs 39 and 40 are adapted to be separated from their engaging contact points and thrust against a ground post 43. Said 40 ground post (when the ground springs 26 and 27 close into contact) is connected with ground G¹ through the winding of the coil 2. The selector A may also be of any suitable type, such as that disclosed in United States Letters Patent No. 815,321. As shown in Fig. 1 it comprises the line relays 50 and 72, the rotary magnet 98^a, private magnet 73, release magnet 230, back-release relay 226, and the bridge-cut-off relay that 45 controls the bridge-cut-off relay springs 58, 59 and 79. Likewise, the connector C may be of the type disclosed in United States Letters Patent No. 815,176, and, as shown, comprises the line relays 125 and 138, the 50 vertical magnet 129, the rotary magnet 143,

the private magnet 141, the ringer relay 161, the release magnet 114, and the back-bridge relays 115 and 116. If the subscriber #500 wishes to make a call he proceeds as follows: If he desires to call the substation #220 he removes his receiver from the switch-hook, operates the vertical push-button 37 twice and the rotary push-button 38 once; again the first button is pressed twice and the second button once; for the last time the button 37 is pressed ten times and the button 38 once. By pressing the button 37 twice for the first digit of the desired number, the shaft of the first-selector A is raised two steps and the switch-shaft wipers 45, 46 and 47 are raised to the second level of the line and private banks.

55 The operation is as follows: When the spring 39 engages the ground post 43 an energizing circuit is established through the vertical line relay 50 of the first-selector A, and in series with the winding of the locking relay 2. The current in this circuit flows from ground G¹ through the winding of the said locking relay 2 to the conductor 51, and through the ground springs 27 and 26 to the conductor 52, to the ground post 43 and spring 39 to the vertical line conductor 53, side switch wiper 54, contact point 55, vertical line relay 50, bridge-cut-off relay springs 58 and 59 to the battery lead 60, and through battery B to ground G. By the first impulse the locking magnet 2 is energized, together with the vertical line relay 50; said locking magnet then attracts its armature 4 and permits the spring 6 to force the angled section 16 over the armature 4, thereby locking said magnet. It will be understood that the said angled section 16 normally rests against the left-hand terminal of the armature 4, as shown at substation #220. As soon as the springs 7 and 8 are forced into contact, as previously stated, the secondary winding 10 of the induction-coil 11 is short circuited. This short-circuit may be traced from the spring 7 to the conductor 70, thence to the secondary winding 10 and to the conductor 71, thence to the spring 8 which, as stated, is in engagement with the spring 7. Furthermore, the springs 8 and 9 being in contact the coil 13 is shunted across the terminals of the receiver 12. This shunt may be traced from the spring 7 to the conductor 70 and to the receiver 12, thence from the other terminal of the said receiver to the coil 13 and to the spring 9, thence through the spring 8 to the spring 7. Each time that the vertical line relay 50 is energized its armature 61 presses the line relay spring 62 onto the ground spring 63, energizing the vertical magnet 64. The circuit through which the current flows for energizing said vertical magnet may be followed by commencing with ground G² and

passing through the springs 63 and 62 to the private springs 66 and 67, through the vertical magnet 64 to the battery lead 60, and through battery B to ground G. Each 5 time that the vertical magnet 64 is energized the vertical armature (not shown) is attracted, and by means of the vertical pawl the shaft is raised, as previously stated. When the subscriber presses the spring 40 10 onto the ground post 43 the rotary line relay 72 of the first-selector A is in turn energized. Said relay closes a circuit through the private magnet 73 as a result, and the latter then permits the side switch to pass 15 from first to second position. The circuit that comprises the said rotary line relay 72 may be traced as follows: from ground G¹ through the relay 2 to the ground post 43, as before, thence to the spring 40, rotary line conductor 74, side switch wiper 75, contact point 76 to the rotary line relay 72, through the bridge-cut-off relay springs 79, 58 and 59 to the battery lead 60, thence 20 through battery B to ground G.

Having once been energized the locking relay 2 at the coin-collecting device F is not further operated for the time being. The rotary line relay 72, however, upon attracting its armature 80 presses the line relay 30 spring 81 onto the ground spring 63 for operating the private magnet 73. The current for said private magnet passes from ground G² through the springs 63 and 81, and through the private magnet 73 to the 35 battery lead 60, thence through battery B to ground G. The private magnet upon operating releases the side switch from first to second position. When the side switch shifts to second position the side switch 40 wipers 54 and 75 leave the contact points 55 and 76 and pass into engagement with the contact points 91 and 92; also, the side switch wipers 93 and 94 leave the contact 45 points 95 and 96 and pass into engagement with the contact points 97 and 98 instead. The closure of connection between the contact point 97 and side switch wiper 93 completes a circuit through the rotary magnet 98^a. The current in this circuit passes from 50 ground G² to the contact point 97, thence through the side switch wiper 93 to the rotary magnet coil 100, thence through the interrupter spring 101 and 102 to the coil 103 and to the battery lead 60, thence 55 through battery B to ground G. When the rotary magnet 98^a is energized, as described, the rotary armature 113 is attracted, thereby rotating the shaft one step, after which the side switch passes to third position. 60 Of course, if the private wiper 47 strikes a grounded private bank contact the shaft will not stop when the wipers reach the first contact of the second level, but will be carried onto the second contact, and so on, as 65 disclosed in the patent cited above. If the

private wiper meets a grounded contact point the private magnet 73 is retained energized even after the rotary armature 113 returns to normal position. As a result the side switch is not permitted to pass to third 70 position, but is locked by the private magnet in the second position until the rotary magnet is again energized, so that the shaft and wipers may be rotated into the next position, and so on until a non-guarded private bank contact is found. Assuming that the shaft wipers are stopped on the first contact of the second level of the line bank from which lead the trunk conductors 121 and 122, the subscriber's line conductors 53 80 and 74 will, when the side switch wipers 54 and 75 pass into engagement with the contact points 119 and 120, as a result of the last operation of the side switch, be connected with the said trunk conductors 121 85 and 122, and the private wiper with the trunk-release conductor 123 that leads to the connector C, as shown in Fig. 1. When the side switch passes to third position, and when the side switch wiper 94 engages the 90 contact point 124, a guarding potential is established at the first contact of the second level of the private bank, by way of the private wiper 47, from ground G⁴ to prevent any other selector from coming in on 95 the seized line. The subscriber's conductors are thus extended to the connector. When the vertical button 37 is pressed twice for the second digit of the number desired, the vertical line relay 125 of the conductor C 100 is energized. Current for energizing said relay passes from ground G¹, as in the previous case, to the ground post 43, thence to the vertical line conductor 53, side switch wiper 54, contact point 119, conductor 126 105 to the vertical line wiper 45, thence to the vertical trunk conductor 121 and through the vertical line relay 125 to the battery lead 60, thence through battery B to ground G. The vertical line relay then causes the 110 line-relay spring 127 to press against the ground spring 128 so that the vertical magnet 129 is energized by a flow of current from ground G⁵ through said springs 128 and 127 and through the private springs 130 and 131 to the side switch wiper 132, contact 115 point 133 to the vertical magnet 129, thence to the battery lead 60 and through battery B to ground G. The vertical magnet 129 upon energizing twice attracts its armature 120 and raises the shaft (not shown) two steps, placing the line and private wipers 145, 146 and 147 opposite the first contact of the second level of their respective banks.

When the rotary button 38 is pressed for the second time the connector rotary line relay 138 is magnetized in turn and the current flows from ground G¹ to the ground post 43, thence through the spring 40, conductor 74, side switch wiper 75, contact 125 130

point 120, conductor 139 and rotary line wiper 46 to the rotary trunk conductor 122, and through the rotary line relay 138 to the battery lead 60 thence through battery B to ground G. Upon being energized the said relay 138 presses the line relay spring 140 against the ground spring 128. As a result the private magnet 141 is energized, the energizing current for which may be traced from ground G⁵ through the said springs 128 and 140 to the private magnet 141, thence to the battery lead 60 and through battery B to ground G. Upon being energized once the private magnet 141, like the private magnet of the first-selector, causes the side switch to pass from first to second position, so that the side switch wiper 132 is shifted from the contact point 133 onto the contact point 142. When the subscriber presses the button 37 ten times for the last digit the vertical line relay 125 is then energized each time as before and over the same circuit; but when the springs 127 and 128 are forced into contact the rotary magnet 143, instead of the vertical magnet 129, is energized, since the side switch wiper 132 is now resting in engagement with the contact point 142. The energizing circuit for said rotary magnet is from ground G⁵, as before, to the side switch wiper 132, thence through the contact point 142 to the rotary magnet 143 to the battery lead 60, and through battery B to ground G. The rotary armature (not shown) being attracted ten times rotates the shaft (not shown) ten times, carrying the switch-shaft wipers 145, 146 and 147 into engagement with the tenth contact of the second level of the line and private banks. The line wipers 145 and 146 are, therefore, placed in connection with the normal conductors 150 and 151, and the private wiper 147 in engagement with the private normal 152. The subscriber for the last time presses the rotary button 38 and grounds the rotary line conductor 74, thereby energizing the rotary line relay 138 over a circuit that has already been traced. The private magnet 141 is again energized once as a result, and the side switch is shifted into third position. As a result the subscriber's extended line conductors 121 and 122 are connected with the normal conductors 150 and 151 at the instant that the side switch wipers 153 and 154 engage with the contact points 155 and 156, respectively. The subscriber then presses his signaling button 157 and thereby presses the spring 158 onto the contact point 159. An energizing circuit is established through the connector vertical line relay 125 from ground G¹ through the coil 2, ground springs 27 and 26, contact point 159 and spring 158 to the contact point 41, thence through the spring 39 to the vertical line conductor 53, and through the vertical line relay 125, as before, to the battery lead 60, thence through battery B to ground G. When the connector side switch passes to third position the side switch wiper 132 engages with the contact point 160, and when the vertical line relay 125 is energized and the springs 127 and 128 placed in contact the ringer relay 161 is thereby magnetized. The current for energizing said relay flows from ground G⁵, as previously described, to the side switch wiper 132, thence through the ringer relay 161 to the battery lead 60, and through battery B to ground G. Said relay upon attracting its armature forces the springs 162 and 163 away from the springs 164 and 165 and into engagement with the springs 166 and 167. As a result the ringer generator 168 is bridged across the normal conductors 150 and 151 and the subscriber's bell 169 at the station #220 is then rung. The ringing current flows from the ringer generator 168 through the ringer relay springs 166 and 162 to the side switch wiper 154, thence through the contact point 156 to the rotary line wiper 146, normal conductor 151, rotary line conductor 170, ringer 169, switch-hook 171 to the vertical line conductor 172, thence to the vertical normal conductor 150, vertical line wiper 145, contact point 155 to the side switch wiper 153, ringer relay springs 163 and 167 to the ringer generator 168. The subscriber at the substation #220 upon hearing the signal removes his receiver 173 from the switch-hook 171 and thereby disconnects the bell 169 from across his line, but substitutes instead his secondary talking circuit comprising the receiver 173 and a secondary winding 174. This secondary circuit across the conductors 170 and 172 may be traced from the contact point 175 to the receiver 173, thence to the secondary winding 174, through the condenser 176, signaling button springs 177 and 178, springs 179 and 180 to the contact point 181. The said contacts 175 and 181 are, of course, directly connected to the line conductors 170 and 172, as shown. Since the locking relay 182 is in normal condition the subscriber at the station #220 will find his apparatus in condition for talking, since the springs 135, 136 and 137 are separated. Upon answering he will speak into his transmitter 183 and thereby induce a current in the secondary winding 174, which current will pass to the line conductors 170 and 172. This current, by way of the heavy line conductors shown in Fig. 1, will reach the line conductors 53 and 74 of the calling substation. The current then passes from the conductor 53 to the spring 39, contact point 41, springs 185 and 184, signaling button springs 158 and 186, condenser 36, conductor 71, springs 8 and 7, conductor 70 to the receiver 12, thence to the contact point 42 and spring 40 to the rotary line conductor 74. Although the coil 2

13 is shunted across said receiver 12 from the springs 8 and 9 to the contact point 42 it does not cut off all the current through the said receiver, so that the calling subscriber 5 is able to hear the called subscriber when he answers. The calling subscriber then drops a coin 14 into a suitable slot to be herein-after described, which coin then strikes the stock 15, releasing the armature 4, as described. The springs 7, 8 and 9 at once separate, so that the subscriber's talking apparatus at the calling substation is restored and connected with the talking apparatus of the called substation. When the subscribers 15 are through talking the calling subscriber restores his receiver 12 to his switch-hook, which, upon descending, causes the cam 23 to force the release springs 30, 31 and 32 into contact. As a result the vertical and rotary line conductors 53 and 74 are grounded simultaneously at ground G¹. The circuit from the said ground to the vertical line conductor 53 passes through the winding 18 of the coil 3 to the release 20 spring 32, thence through the springs 31 and 30 to the vertical line conductor 53, and from the release spring 31 the connection is established to the rotary line conductor 74. Both line conductors being grounded simultaneously the switching apparatus is released in a well-known manner—that is, the line relays 125 and 138 of the connector C are energized simultaneously over circuits that have been described, and as a result 30 the trunk release springs 117 and 118 are brought into contact and the release magnet 114 of the connector is energized in series with the back-release relay 226 of the selector A over the circuit established from 35 ground G⁴ at the selector A to battery B. As is well known the switch-shaft of the connector C falls to normal position at once, and the back-release relay 226 of the selector A causes the energization of the release 40 magnet 230 by pressing the back-release relay springs 228 and 229 into contact, establishing an energizing circuit through the release magnet 230 from ground G⁸ to the battery B. Of course, when the ground is 45 removed from the line the magnets of the connector and selector are deenergized, restoring the switches. Had the called subscriber been busy the connector C would not have established connection with the 50 called line, but would have been released instead. As is well known, this release occurs when the called subscriber grounds the rotary line conductor 74 for the last time when, of course, the private magnet 141 of 55 the connector C energizes, carrying the springs 148 and 149 into contact, whereby the release magnet 114 is energized by a flow of current from the private wiper 147, which is at the time in connection with the 60 grounded contact, through the said springs. 65

148 and 149 to the release magnet 114 and to battery B, with the result that the connector switch shaft is released and the connector side switch restored to first position.

Then when the signaling button 157 is pressed, as described, the vertical magnet 129 and not the ringer relay 161 is energized. As a result the switch-shaft is raised and the switch-shaft springs 187 and 188 are closed into contact, and busy signaling 70 current from the coil 189 is sent out over the line of the calling subscriber through the springs 187 and 188 to the contact point 190, thence to the side switch wiper 154, ringer relay springs 162 and 164, condenser 80 191 to the rotary trunk conductor 122, first-selector rotary line wiper 46, contact point 120, side switch wiper 75, rotary line conductor 74, and through the receiver 12 and coil 13 in multiple, as already described, 85 condenser 36 to the vertical line conductor 53, thence to the side switch wiper 54, contact point 119, vertical line wiper 45, and vertical trunk conductor 121 to the vertical line relay 125, thence to the battery lead 60 90 and to the coil 189. The calling subscriber, upon hearing the busy-signal, instead of dropping the coin, as described, will hang up his receiver and establish a flow of current through the winding 18 of the coil 3, 95 as already described, to the vertical and rotary line conductors 53 and 74, and thence through the vertical and rotary line relays 125 and 138 of the connector C, over circuits that are already familiar to the battery lead 100 60 and through battery B to ground G. Said relay 3 upon being magnetized attracts its armature 192 which withdraws the latch 5 from the armature 4, permitting said armature to be restored, as already stated and 105 for the purpose that has already been pointed out.

If the subscriber at the substation #500 wishes to communicate with the central office he operates his calling device in accordance with the number that he wishes to call. Assuming that the number of the central operator is 0 he operates the vertical button 37 ten times and thereby raises the first-selector shaft to the tenth level in a manner 110 described. He then presses the rotary button 38 once so as to operate the private magnet 73 in order that the side switch may pass to second position, and that the rotary magnet 98^a may be operated as before to 115 carry the wipers 45 and 46 into contact with the trunk conductors 193 and 194 that lead to the cord circuit E. The subscriber then presses the signaling button 157 and thereby grounds the vertical line conductor 53, 120 and as a result the relay 206 is energized over the following circuit: from ground G¹ to the vertical line conductor 53, as previously described, thence to the side switch wiper 54, contact point 119, conductor 126, 125 130

vertical line wiper 45, conductor 193, relay 206, and through battery B to ground G. The energization of the relay 206 causes its armature to place the springs 214 and 215 in contact, thereby closing an energizing circuit through the drop 195 extending from ground G through the springs 214 and 215, springs 218 and 219, conductor 204 through the drop 195, thence through battery B to ground G. When the operator sees the signal she will operate a key to close the springs 216 and 196 in contact and the springs 217 and 203 in contact. As soon as the said springs close into contact an energizing circuit is established through the winding 17 of the substation release coil 3. The current in this circuit flows from ground G through the springs 216 and 196, thence to the conductor 193, vertical wiper 45, conductor 126, contact point 119, side switch wiper 54, vertical line conductor 53, spring 39, contact point 41, springs 185 and 184, signal button spring 158, contact point 186 to the winding 17 of the coil 3, thence through the locking magnet springs 8 and 9, resistance coil 13 to the contact point 42, spring 40, rotary line conductor 74, side switch wiper 75, contact point 120, conductor 139, rotary line wiper 46, conductor 194, springs 203 and 217, coil a, and through the battery B to ground G. Upon being energized the release coil 3 attracts the armature 192 and withdraws the latch 5 from the armature 4 so that the springs 7, 8 and 9 are separated in order that the calling subscriber may be able to converse with the central office operator without having to deposit a coin. It will be noticed that the operator's receiver 219a with the secondary winding 220 of the induction-coil 221 and condenser 222 are connected in series with the springs 211 and 212, and when the key is thrown in the opposite direction, first the springs 216 and 196 and the springs 203 and 217 are separated to restore the substation release coil 3, and then the operator's set is bridged across the calling line. The circuit from the subscriber's line conductors through the said receiver may be traced as follows: from the vertical line conductor 53 to the side switch wiper 54, contact point 119, conductor 126, vertical line wiper 45, vertical trunk conductor 193, springs 213 and 212, receiver 219, secondary winding 220 of the induction-coil 221, condenser 222 to the springs 211 and 199, conductor 194 to the rotary line wiper 46, conductor 139, contact point 120, side switch wiper 75, and to the rotary line conductor 74. Being thus connected the operator and calling subscriber may, of course, converse in a well-known manner, the subscriber talking into his transmitter 33 and the operator into the transmitter 223. When the subscriber and the operator are through talking, if the sub-

scriber hangs up his receiver he grounds the vertical and rotary line conductors 53 and 74, as previously described, and as a result energizes the relays 205 and 206 of the cord circuit E simultaneously. The current 70 through the former coil passes from the vertical line conductor 53 to the side switch wiper 54, contact point 119, conductor 126, vertical line wiper 45, vertical trunk conductor 193 to the coil 206, thence through battery B to ground G. The other relay is energized by current flowing from the rotary line conductor 74 to the side switch wiper 75, contact point 120, conductor 139, rotary line wiper 46, rotary trunk conductor 194 to the relay 205, thence through battery B to ground G. The said relays 205 and 206 being energized simultaneously they attract their armatures at the same time and thrust the springs 224 and 225 85 into contact. An energizing circuit is therefore established through the back-release relay 226 of the first-selector A from ground G at the said first-selector to the side switch contact point 124, side switch 90 wiper 94, back-release relay 226 to the private wiper 47, private trunk conductor 227, resistance-coil 227a, springs 225 and 224, and through battery B to ground G. When the back-release relay 226 becomes energized the springs 228 and 229 are pressed into contact. As a result the release magnet 230 is magnetized by a flow of current from ground G through the said springs 228 and 229 to the release magnet 230, thence to the battery lead 60 and through battery B to ground G. It will be noticed that when both relays 205 and 206 are energized simultaneously the circuit through the drop 195 is broken, and thus the operator 100 does not receive a false signal. When the release springs 30, 31 and 32 disengage the ground connection to the said subscriber's line conductors is broken, the relays 206 and 205 are deenergized as a result, and, of course, the back-release relay 226 becomes de-magnetized, and the first-selector A is restored.

The coin-collecting device F, shown in Figs. 2, 3 and 4, is constructed as follows: 115 In general appearance the coin-collecting machine resembles a small savings bank. It comprises two parts, the circuit-controlling mechanism J and a box K beneath said circuit-controlling mechanism for receiving 120 the coins as they pass through the circuit-controlling device. The instrument as a whole is assembled on the base M and is adapted to be secured to any suitable support L, a part of the telephone, for instance. This base may be of any suitable material, with holes for admitting the screws 231. The mechanism is protected by a cover N which has on its under edge lugs 232 that are adapted to fit into the slots 233, 130

as more clearly shown in Fig. 11. When the cover is first put in place the terminal 234 of the lug 232 clears the edge 235 of the slot 233, but upon entering in position 5 the cover N is moved in the direction of the arrow so that the edge 235 of the slots 233 may enter into the slots 236. When thus driven into position the bolt 237 of the lock 238 is carried opposite an aperture 239 10 (Fig. 3) so that when the key 240 is turned the said bolt 237 may enter the said aperture 239 for locking the cover in place. It will be understood, of course, that the lock 238 is secured to the cover N by screws or 15 by any other method that may be desired. As shown in Figs. 2 and 4 there is secured at the upper left-hand corner of the base M a short joint of conduit 241 for admitting the cable that conducts the wires from the 20 telephone proper to the circuit-controlling mechanism. At the upper right-hand corner of the cover N there is a coin-slot 242, shown in Figs. 2, 3, 4 and 5, through which the money is dropped onto a ledge, to be hereinafter described, and then seat on its downward course when the subscriber presses the 25 button 243. The said button is maintained in normal position by a spring 244 (Fig. 5). The circuit-controlling mechanism is mounted upon a frame O, shown in Fig. 6. On the right-hand side this frame is provided with a couple of threaded holes 245 and 246 for securing the said frame in place.

There is a metal shelf 247, shown in Figs. 35 2, 3 and 4, formed by a band bent into three sides of a square. The open side of the square is to the front. The side opposite this front is secured to the base M by screws 248. At the under edges of this metal piece 40 there are secured lugs 249, more clearly shown in Fig. 2. This metal piece acts as a shelf or cradle into which the frame O is set. The said frame O is secured by screws 250 to the said metal piece or shelf 247. The 45 screws 250 are embedded in the holes 245 and 246 so that the said frame O is securely held in place. The locking and releasing magnets 2 and 3 (Fig. 1) are set up within the frame O and secured thereto by screws 50 251 to the bottom of said frame, said screws passing through the openings 252. The armature 4 of the coil 2 is, as shown, pivotally mounted upon the upright 253, and the armature 192 of the coil 3 is pivoted upon 55 the section 254. There are two lugs 255 and 256 opposite the place allotted to the magnet 2 and between which the latch 5 is pivotally mounted. The stock 15 of said latch is shown in Fig. 6 projecting beyond the outer 60 surface of the front wall 257 of the frame O. Normally the armature 4 and latch 5 are in such a position with relation to each other that the end 16 rests upon the circumference of the armature 4; but there is a 65 spring 6 which, if the armature 4 is attract-

ed, carries the terminal 16 over the armature 4 and locks it in its attracted position. Near the base of the section 253 that supports the armature 4 there are suitable openings 260 to which the springs 7, 8 and 9 are fastened, 70 which springs extend upwardly in front of the downwardly-projecting angled section 261 of the armature 4, as clearly shown in Fig. 4. As indicated, the front and back sections 257 and 253 are given rigidity by 75 means of the bolt 262. The spring 7 normally rests against the armature 4 and provides sufficient tension for retaining said armature in normal position. If the called subscriber does not answer when the calling 80 subscriber energizes his release coil 3 by pressing the release springs 30, 31 and 32 together for releasing the central office apparatus, the arm 263 of the armature 192 engages the locking latch 5 and pushes the end 85 16 out of engagement with the armature 4. The armature 4 returns to normal position and the springs 7, 8 and 9 disengage, leaving the substation talking circuits in normal condition. When the release coil 3 becomes 90 deenergized the retracting spring 259 provides sufficient tension to restore the said armature to normal position.

In connection with the circuit-controlling device, there is provided a coin-selecting 95 means whereby when a coin of improper size is dropped into the slot the coin will be rejected; but if a coin of proper size is introduced into the machine the coin will pass through and produce the desired results. For instance, if the machine is adjusted to receive nickel pieces, then when cent pieces are dropped instead the same will run out of the machine, while the nickel pieces will pass through and operate 100 the mechanism. The trough P through which the money passes is shown in Fig. 7. It is attached to the frame O on the front wall 257 just opposite the latch 5. The screws 264 are adapted to engage the 105 openings 265 in said wall for retaining the trough in position, as indicated in Fig. 2. The trough proper is very simple and is made of two plates 266 and 267. The plate 266 as shown is grooved. It has a main 110 groove or channel 268 that extends from the top 269 to the bottom 270. There is a branch 271 to this groove or slot that passes to the right and which terminates in the cup 272. Said channel 271 is provided for ejecting 115 improper coins, namely coins that are smaller than those for which the machine is adjusted. The plates 266 and 267 have cut through them two sections 273 and 274 that are connected by a narrow slot 275. Above 120 said sections 273 and 274 there is another slot 276 which is horizontally disposed. A sliding member 277 (Fig. 12) is adapted to engage the plates 266 and 267 through the 125 openings 273, 274, 275 and 276 in the follow- 130

ing manner: The face or shelf 278 of the member 277 enters the horizontal slot 276 within which slot it is adapted to slide. Upon the back of the plate 267 and right opposite the slot 276 there is a guide 279 which is shown in top view in Fig. 8. The right wing 280 of the member 279 is folded over to the left for guiding the right edge 281 of the member 277. Said guide 279, as shown 10 in bottom view in Fig. 9, is secured to the plate 267 by the screws 282. The left-hand side of the member 279 is turned up at right angles to the horizontal section 283 of said member to form a guide 284, as shown in Fig. 4. The sliding piece 277 is provided with a slot 285 that engages said angled section 284, as shown in Fig. 8. The section 278 that carries the slot 285 carries in addition two other slots 286 and 287. The slot 286 20 is provided as a guide-channel that receives a screw 288, said screw being embedded in the guide member 279, as shown in Fig. 8. The front face 289 of the sliding member 277 has a rearwardly-projecting pin 290. The said pin operates in the hole 291 that pierces the plates 266 and 267. The projections 292 and 293 of the sliding member 277 operate respectively within the cut sections 273 and 274, while the part 294 of the metal 30 from which the said sections 292 and 293 project operates in the slot 275. Offset from the projection 292 there is a finger 295 that extends above the section 292 and that operates in the slot 296 at the upper right-hand side of the opening 273. The plane of said finger 295 is at right angles to the plane of the members 293 and 294, and said finger normally rests within the channel 271, acting as an obstruction to prevent legitimate 35 coins from rolling out to the cup 272. A screw 297, shown in Fig. 8, is fastened in the opening 298, shown in Fig. 12, and to this screw a retracting-spring 299 has one end attached and the other end secured to a 40 suitable screw upon the plate 267. The object of this retracting-spring is to provide a means whereby, when the sliding member 277 is pressed inwardly, it (the sliding member) may be withdrawn into normal position 45 automatically.

The coin-selecting mechanism operates as follows: Referring to Fig. 5 it will be seen that if a coin is dropped into the slot 242 it will enter part way and rest upon the 50 sliding member 277 (upon the face 278) at about a point marked by the line 300 (Fig. 12). The calling subscriber having previously made his call in the manner that has been described, when the called subscriber 55 answers drops the coin as stated and presses the button 243, thus advancing the sliding member 277 so that the finger 295 that normally rests within the channel 271 is driven beyond said channel. When the said button 60 243 is pressed as stated, as the finger 295 begins to leave the channel 271 the pin 290 begins to advance within the hole 291, across the perpendicular channel 268, and at the same time the flanges 292 and 293 begin to travel inwardly in the slots 273 and 274, 65 respectively. Very soon the said flanges 292 and 293 pass beyond the channel 268, and the sloping section 294 from which the said flanges project obstructs the said channel 268, as shown in Fig. 4. When the sliding 70 member 277 reaches the inward limit of its stroke the coin that has been resting upon the shelf 278 drops through the slot 287, if it is not too large to pass through the slot 301, and passes through and is caught between the pins 290 and 302 (Fig. 14). Said pin 302 is permanently screwed onto the back plate 267 and limits the breadth of said channel 268, as shown in Fig. 7. If the coin is too small it passes between the pins 290 and 302, as shown in Fig. 13, and strikes the sloping section 294 and rolls out through the channel 271 into the cup 272. If the coin is of proper size, however, it remains hanging between the pins 290 and 302, as shown in Fig. 14, until the sliding member 277 recedes sufficiently to permit the pin 290 to leave the channel 268, by which time also the finger 295 is again across the channel 271. The coin then drops through 75 the channel 268 behind the flanges 292 and 293 and down through said channel until it strikes the stock 15 of the latch 5. It will be noticed that the lower end of the plate 267 is cut away at 303, so that the said stock 15 may normally rest within the path of the coin 14, as shown in Fig. 10. When the latch 5 is operated the armature 4 regains its normal position and the calling subscriber may then converse with the called subscriber. The object in providing the flanges 292 and 293 is as follows: Someone 80 may, with the intention of defrauding the machine, drop a coin smaller than the coin required into the slot 242, and by tapping the button 243 catch the small coin between the slot 287 and the neck 269 (Fig. 4); then by further tapping the button 243 the sliding member 277 and the coin will be released, which sliding member upon immediately jumping forward clears the sloping section 294 from the channel P while the coin is falling. The said flanges are provided to catch (in such an event) the coin between them and the plate 266, and thus 85 prevent the clearing of the passage P. The coin will, of course, be held there until the button 243 is again pressed, at which time the coin will roll out of the machine to the cup 272. It will be evident that it is desirable 90 that the flanges, and especially the flange 293, extend upwardly as high as possible and to such a distance that when the

upper circumference of the coin leaves the slot 287 there will be a very small space for the coin to travel before it falls within the path of the flanges 292 and 293. Just below the bottom extremity of the channel 268 the money box K is provided with a funnel 304 in which the coin drops and falls from thence into the box K. Said box is provided with a suitable locking key for opening said box, when it is desired, to remove the money that has been collected.

In Figs. 2 and 3 there is shown to the left side of the shelf 247 a terminal clip 305 comprising the springs 306, 307, 308, 309, 310, 15 311, 312 and 313. This clip is secured to the flange 314 in any suitable manner, while the springs are properly insulated from each other. There is a corresponding clip 315 comprising the springs 316, 317, 318, 319, 20 320, 321, 322 and 323 that is secured to the frame O by suitable screws 324. Said springs are the terminals of all leads for the relays and springs of the coin-collecting attachment. Said last springs, in the order 25 named, are adapted to engage the springs 306, 307, 308, 309, 310, 311, 312 and 313, respectively, when the frame O is in place. All connections from the telephone terminate 30 in the last-named set of springs and from thence branch through the first-named set of springs to the several circuits shown in Fig. 1. When the subscriber calls the manual operator he connects with the cord circuit E, as described, after energizing and 35 locking the relay 2; then when the said operator energizes the release magnet 3, the armature 192 is attracted and the member 263 (Fig. 6) drives the link 5 out of engagement with the armature 4, releasing said 40 armature as described. The winding of the relays 2 and 3 may be of any suitable resistance, but with a central battery of fifty volts good results are obtained when the relay 2 is wound to a resistance of thirty ohms; 45 the winding 18 of the relay 3 to thirty ohms, and the winding 17 of the same relay to three hundred and twenty ohms. In the cord circuit E the coil 227^a is wound to sixty ohms; the relays 205 and 206 to five hundred ohms; 50 the coil 195 to two thousand ohms; and the coil 'a' to forty-five ohms.

From the foregoing it will be seen that I provide means by which an automatic subscriber may use his telephone for conversing with another subscriber by first calling the subscriber and then, in the event of obtaining connection with the called subscriber's line, depositing a coin in the slot of the receptacle containing the coin-controlled mechanism. It will be seen that provision is made whereby the calling subscriber's telephone apparatus is not rendered inoperative to the extent of preventing him from hearing the called sub-

scriber when the latter answers. At the same time, however, as explained, the calling subscriber cannot, even if he hears the called subscriber answer, use his telephone for talking until after he deposits a coin in the slot of the money receptacle. In this way the calling subscriber can hear the called subscriber answer, but no conversation can be carried on between the two subscribers until after the calling subscriber pays toll by depositing the required coin in the slot of the money box. In case of trouble, however, as fully explained, the calling subscriber can converse with the operator without the necessity of depositing a coin in the slot. It will be understood, however, that I do not limit myself to the exact construction shown and described.

What I claim as my invention is:

1. In a telephone exchange system, the combination of a calling subscriber's telephone line, a called telephone line, automatic means for enabling the calling subscriber to establish connection with the called telephone line, pay-station apparatus for preventing the calling subscriber from talking over his line until after he deposits a coin in said apparatus, a switchboard operator's equipment, and means for permitting the calling subscriber to talk with the operator without paying.

2. In a telephone exchange system, the combination of subscribers' telephone lines, trunk lines, automatic switches for connecting telephone lines through the medium of said trunk lines, pay-station apparatus for preventing any calling subscriber from conversing with a called subscriber until after a coin is deposited in said apparatus, a switchboard operator's equipment, and means for permitting any called subscriber to converse with the operator without paying.

3. In a telephone exchange system, the combination of a calling subscriber's telephone line, a called telephone line, automatic means for enabling the calling subscriber to establish connection with the called telephone line, pay-station apparatus for preventing the calling subscriber from talking over his line until after he deposits a coin in said apparatus, a switchboard operator's equipment, and means for permitting the calling subscriber to talk with the operator without paying, each telephone line provided at its inner end with an individual line-relay.

4. In a telephone exchange system, the combination of subscribers' telephone lines, trunk lines, automatic switches for connecting telephone lines through the medium of said trunk lines, pay-station apparatus for preventing any calling subscriber from conversing with a called subscriber until after a coin is deposited in said apparatus, a

- switchboard operator's equipment, and means for permitting any calling subscriber to converse with the operator without paying, each telephone line provided at its inner end with an individual line relay. 5
5. In a telephone exchange system, the combination of a calling subscriber's telephone line, a called telephone line, automatic means for enabling the calling subscriber to establish connection with the called telephone line, pay-station apparatus for preventing the calling subscriber from talking over the line until after he deposits a coin in said apparatus, a switchboard operator's equipment, and means for permitting the calling subscriber to talk with the operator without paying, each subscriber's substation provided with a pair of pay-station relays. 10
10. In a telephone exchange system, the combination of subscribers' telephone lines, trunk lines, automatic switches for connecting telephone lines through the medium of said trunk lines, pay-station apparatus for preventing any calling subscriber from conversing with a called subscriber until after a coin is deposited in said apparatus, a switchboard operator's equipment, and means for permitting any calling subscriber 15 to converse with the operator without paying, each subscriber's substation provided with a pair of individual line relays. 20
15. In a telephone exchange system, the combination of a calling subscriber's telephone line, a called telephone line, automatic means for enabling the calling subscriber to establish connection with the called telephone line, pay-station apparatus for preventing the calling subscriber from 25 talking over his line until after he deposits a coin in said apparatus, a switchboard operator's equipment, and means for permitting the calling subscriber to talk with the operator without paying, each subscriber's 30 substation provided with an induction-coil, and a normally open shunt or short-circuit extending around one of the windings of said coil. 40
20. In a telephone exchange system, the combination of subscribers' telephone lines, trunk lines, automatic switches for connecting telephone lines through the medium of said trunk lines, pay-station apparatus for preventing any calling subscriber from 45 conversing with a called subscriber until after a coin is deposited in said apparatus, a switchboard operator's equipment, and means for permitting any calling subscriber to converse with the operator without paying, each subscriber's substation provided with a pair of individual line relays. 50
25. In a telephone exchange system, the combination of a calling subscriber's telephone line, a called telephone line, automatic means for enabling the calling subscriber to establish connection with the called telephone line, pay-station apparatus for preventing the calling subscriber from 55 talking over his line until after he deposits a coin in said apparatus, a switchboard operator's equipment, and means for permitting the calling subscriber to talk with the operator without paying, each subscriber's 60 substation provided with an induction-coil, and a normally open shunt or short-circuit extending around one of the windings of said coil. 65
30. In a telephone exchange system, the combination of a secondary circuit comprising a receiver and a secondary winding, a relay and means controlled thereby to short-circuit the said secondary winding and shunt the said receiver, and measured service means controlling said relay directly by a coin. 70
35. In a telephone exchange system, the combination of a secondary circuit comprising a receiver and a secondary winding, a relay, and a latch for locking the armature of said relay, whereby the said secondary winding may be maintained short-circuited and the said receiver shunted, and means mechanical only, for controlling said latch by a coin. 75
40. In a telephone exchange system, the combination of a secondary circuit comprising a receiver and a secondary winding, a relay, a latch for locking the armature of said relay, whereby the said secondary winding may be maintained short-circuited and the said receiver shunted, and means mechanical only, for controlling said latch by a coin. 80
45. In a telephone exchange system, the combination of a secondary circuit comprising a receiver and a secondary winding, a relay, a coin controlled latch for locking the armature of said relay, whereby the said secondary winding may be maintained short-circuited and the said receiver shunted, a release relay for unlocking said armature, and means mechanical only, for controlling said latch by a coin. 85
50. In a telephone exchange system, the combination of a secondary circuit comprising a receiver and a secondary winding, a relay, a coin controlled latch for locking the armature of said relay, whereby the said secondary winding may be maintained short-circuited and the said receiver shunted, a release relay for unlocking said armature, and means mechanical only, for controlling said latch by a coin. 90
55. In a telephone exchange system, the combination of a secondary circuit comprising a receiver and a secondary winding, a relay, a coin controlled latch for locking the armature of said relay, whereby the said secondary winding may be maintained short-circuited and the said receiver shunted, a release relay for unlocking said armature, and means mechanical only, for controlling said latch by a coin. 95
60. In a telephone exchange system, the combination of a secondary circuit comprising a receiver and a secondary winding, a relay, a latch for locking the armature of said relay, whereby the said secondary winding may be maintained short-circuited and the said receiver shunted, and a release relay for unlocking said relay, and means mechanical only, for controlling said latch by a coin. 100
65. In a telephone exchange system, the combination of a secondary circuit comprising a receiver and a secondary winding, a relay, a latch for locking the armature of said relay, whereby the said secondary winding may be maintained short-circuited and the said receiver shunted, and a release relay for unlocking said relay, and means mechanical only, for controlling said latch by a coin. 105
70. In a telephone exchange system, the combination of a central battery, a subscriber's pay-station, a receiver and a secondary winding, a central office with switching machinery, adapted to be operated by current controlled from the said pay-station, a locking relay for said pay-station, adapted to be energized at the first electric impulse sent to the central office from the pay-station, and a latch for locking said relay, 110 whereby the said secondary winding may be retained short-circuited and the said receiver shunted, a release relay, release circuits for restoring the central office switches, one of said circuits including said release relay, said latch controlled by said release relay, whereby when the central office switches are released from the said pay- 115
75. In a telephone exchange system, the combination of a central battery, a subscriber's pay-station, a receiver and a secondary winding, a central office with switching machinery, adapted to be operated by current controlled from the said pay-station, a locking relay for said pay-station, adapted to be energized at the first electric impulse sent to the central office from the pay-station, and a latch for locking said relay, 120 whereby the said secondary winding may be retained short-circuited and the said receiver shunted, a release relay, release circuits for restoring the central office switches, one of said circuits including said release relay, said latch controlled by said release relay, whereby when the central office switches are released from the said pay- 125

station the said release relay unlocks the said locking relay and restores the circuits which it controls.

15. In a telephone exchange system, the combination of a central battery, a subscriber's pay-station, a receiver and a secondary winding, a central office with switching machinery, adapted to be operated by current sent from the said pay-station, a locking relay for said station, adapted to be energized at the first electric impulse sent from the pay-station, and a latch for locking said relay, whereby the said secondary winding may be retained short-circuited and the said 10 receiver shunted, a release relay for said station, a line circuit connecting the subscriber's station with the main office and including said release relay, whereby when the battery is bridged across the subscriber's 15 line at the central office the said release relay is energized to restore the locking relay.

16. In a measured service telephone exchange system, the combination of a substation, a selector-switch, a cord circuit comprising a pair of relays, a release circuit controlled by the subscriber and including said relays; a trunk-release circuit controlled by said relays and including a back-release relay of the said selector in series with a resistance-coil, and means whereby the calling subscriber may use said relays free of charge.

17. In a measured service telephone exchange system, the combination of a subscriber's station, a central station, and a line connecting the said subscriber's station with the central station, a cord circuit and a selector-switch adapted to connect the said line with the said cord circuit, a release circuit comprising a release relay at the cord circuit, a line signal, a second release relay, and means whereby the calling subscriber may use said relays free of charge.

18. In a measured service telephone exchange system, the combination of a cord circuit comprising a listening key and operator's key springs, a subscriber's station and telephone line, a selecting switch for said line, adapted to connect the said line with the said cord circuit, a locking relay at said station for controlling the talking circuit thereof, and a release relay for unlocking the said locking relay, said key springs adapted when operated to bridge a central battery across the subscriber's line for energizing the said release relay, whereby the calling subscriber may call the operator at the cord circuit free of charge.

19. In a measured service telephone exchange system, the combination of a central office and a substation, a central battery, a resistance-coil, a locking relay for controlling the talking circuit at said substation, a release relay for controlling the said locking

relay, a subscriber's telephone line, a selector-switch at the central office allotted to said subscriber's line, a central office cord circuit, normally open key springs 216 and 196, listening springs 212 and 213 and 199 and 211 also normally open, normally open 70 switching springs 203 and 217, the switching spring 196 and the listening spring 213 being in multiple and connected with one side of the cord circuit, the springs 203 and 199 being connected in multiple to the other side 75 of the cord circuit, the switching springs 216 and 196 and 217 and 203 adapted to be operated to bridge the battery in series with said resistance-coil across the subscriber's line for energizing the substation release relay and restoring the substation talking circuits, and the listening springs 212 and 218 and 199 and 211 adapted to be closed to bridge the operator's talking circuit across the line.

20. In a telephone exchange system, a calling and a called subscriber's line, means including an automatic switch for establishing connection between said lines, a transmitter and receiver and a calling device on 80 said lines, said calling device controlling the operation of said automatic switch, a measured service device, means for rendering said transmitter inoperative upon the initial operation of said calling device, a telephone 85 set at the central office adapted to be connected with a calling subscriber's line, and means in said telephone set for rendering said transmitter operative.

21. In a telephone exchange system, a calling and a called subscriber's line, means including an automatic switch for establishing connection between said lines, a transmitter and a receiver and a calling device on 90 said lines, said calling device controlling the 95 operation of said automatic switch, a measured service device, a relay for controlling the same, means for energizing said relay upon the initial operation of said calling device, means controlled by the energization of 100 said relay for rendering said transmitter inoperative, a telephone set at the central station adapted to be connected with the calling subscriber's line, and means in said talking 105 set for again rendering said transmitter operative.

22. In a telephone exchange system, a calling and a called subscriber's line, means including an automatic switch for establishing connection between said lines, a transmitter and a receiver and a calling device on 110 said lines, said calling device controlling the 115 operation of said automatic switch, a measured service device, a relay for controlling the same, means for energizing said relay upon the initial operation of said calling device, means controlled by the energization of 120 said relay for rendering said transmitter 125 operative.

- inoperative, a telephone set at the central station adapted to be connected with the calling subscriber's line, a second relay at the substation, and means associated with said talking set for energizing said second relay for again rendering said transmitter operative.
23. In a telephone system, the combination of a secondary circuit comprising a receiver and a secondary winding, a relay and means controlled thereby to short circuit the said secondary winding and to shunt said receiver, and means mechanical only directly controlled by a coin and directly controlling the armature of said relay.
24. In a telephone exchange system, the combination of a secondary circuit comprising a receiver and a secondary winding, a relay, a latch for locking the armature of said relay, whereby the said secondary winding may be maintained short-circuited and the receiver shunted, and means mechanical only directly controlled by a coin and directly controlling said latch for restoring said relay.
25. In a telephone exchange system, the combination of a secondary circuit comprising a receiver and a secondary winding, a relay, a latch for locking the armature of said relay, whereby the said secondary winding may be maintained short-circuited and the said receiver shunted, a release relay for unlocking said armature and means to control the operation of the release relay, and purely mechanical instrumentalities for restoring the first relay.
26. In a telephone exchange system, the combination of a secondary circuit comprising a receiver and a secondary winding, a relay, a latch for locking the armature of said relay, whereby the said secondary winding may be maintained short-circuited and the said receiver shunted, a release relay for unlocking said armature and means to control the operation of the release relay, and means whereby a suitable coin is made to unlock said armature through the medium of purely mechanical instrumentalities.
27. In a telephone exchange system, the combination of a secondary circuit comprising a receiver and a secondary winding, and toll controlled means comprising a relay and a latch for locking the armature of said relay whereby the said secondary winding may be maintained short circuited and the said receiver shunted and electromagnetic means for controlling said latch, electrically disconnected from said toll controlled equipment.
28. In a telephone exchange system, the combination of a secondary circuit comprising a receiver and a secondary winding, and toll controlled apparatus comprising a relay, a latch for locking the armature of said relay whereby the said secondary winding may be maintained short circuited and the said receiver shunted, and a release relay for unlocking said armature, electrically disconnected from said toll controlled equipment.
29. In a telephone exchange system, the combination of a secondary circuit comprising a relay and a secondary winding, a toll controlled apparatus comprising a relay and a latch for locking the armature of said relay whereby the said secondary winding may be maintained short circuited and the said receiver shunted, a release relay for unlocking the said armature, the said toll equipment comprising means also whereby the said armature may be unlocked by purely mechanical means.
30. In a telephone exchange system, the combination of a secondary circuit, comprising a receiver and a secondary winding, toll controlled apparatus comprising a relay and a latch for locking the armature of said relay whereby the said secondary winding may be maintained short circuited and said receiver shunted, the said toll controlled equipment comprising means mechanical only directly controlled by a coin and directly controlling the armature of said relay.
31. In a telephone exchange system, the combination of a secondary circuit comprising a receiver and a secondary winding, a relay, and a latch for locking the armature of said relay, whereby the said secondary winding may be maintained short circuited and the said receiver shunted, mechanical means only, for controlling said latch by a coin, and independent electrical means for also controlling said latch.
32. In a telephone exchange system, the combination of a secondary circuit comprising a receiver and a secondary winding, a relay, a latch for locking the armature of said relay, whereby the said secondary winding may be maintained short circuited and the said receiver shunted, a release relay for unlocking said armature, mechanical means only, for controlling said latch by a coin, and independent electrical means for also controlling said latch.

Signed by me at Chicago, Cook county, Illinois, this 9th day of October, 1906.

FRITZ LUBBERGER.
